UNITED STATES PATENT OFFICE.

BETHUEL M. DAVIS, OF CHICAGO, ILLINOIS, ASSIGNOR, BY MESNE ASSIGNMENTS, TO HILO GUM COMPANY.

DESIGN FOR A CASING FOR VENDING-MACHINES.

No. 39,257.

Specification for Design.

Patented April 7, 1908.

Application filed December 13, 1907. Serial No. 406,279. Term of patent 3½ years.

To all whom it may concern:

Be it known that I, BETHUEL M. DAVIS, a citizen of the United States, residing at Chicago, in the county of Cook and State of Illinois, have invented a new, original, and ornamental Design for a Casing for a Vending-Machine, of which the following is a specification, reference being had to the accompanying drawing, forming part thereof.

The single figure in the case is a perspective drawing of the design.

What I claim is:—

The ornamental design for a casing for a vending machine.

BETHUEL M. DAVIS.
